FIG. 1.

FIG. 2.

Inventor

Sherman Belveal

By *Clarence A. O'Brien*
Attorney

UNITED STATES PATENT OFFICE

SHERMAN BELVEAL, OF DELPHOS, KANSAS, ASSIGNOR OF ONE-HALF TO LLOYD I. BELVEAL, OF KANSAS CITY, MISSOURI

FASTENER

Application filed February 12, 1930. Serial No. 427,795.

This invention appertains to new and useful improvements in fasteners, and more particularly to a novel fastener for use on garment suspenders.

5 The principal object of this invention is to provide a spring fastener for suspenders which in use will serve to readily adapt the suspenders to normal movements of the body.

Another important object of the invention 10 is to provide tensioning means for suspenders for causing the suspenders to automatically adjust themselves to the body of the person wearing the same.

These and numerous other important 15 objects and advantages of the invention will more readily become apparent to the reader after a consideration has been given to the following specification and claim.

In the drawings:—

20 Figure 1 represents a side elevational view of the novel fastener.

Fig. 2 represents an edge elevational view of the novel fastener.

Fig. 3 represents a vertical sectional view 25 taken substantially on the line 3—3 of Fig. 2.

Referring to the drawings wherein like numerals designate like parts, it can be seen that the present invention includes a substantially rectangular-shaped jacket 5, although 30 of substantially thin construction.

One end of the jacket is provided with a pair of openings to receive the ends of a bail 6, the ends of the bail being bent outwardly against the inner side of the jacket so as to 35 prevent displacement of the bail from the jacket.

The opposite end of the jacket is provided with a pair of openings to receive slidably, the leg portions of the U-shaped member 7. 40 This U-shaped member 7 has a compressible coiled spring 8 convoluted around the same throughout its entire length, the ends of the said spring being adapted to impinge against the inner side of the last-mentioned end of 45 the jacket 5.

The free ends of the U-shaped member 7 extend outwardly of the jacket 5 and are provided with eyes 9 for linked connection with the eyes 10, on the free ends of the U-shaped 50 button engager 11. The end portions of the

legs of this button engager 11, flare outwardly so as to permit the button to be engaged thru the engager, after which the reduced portion thereof is engaged between the button and the garment, in substantially the 55 manner shown in Fig. 1.

Obviously, when any extraordinary stress is imparted to the suspender, the same will be taken up by compression of the spring 7 and the extension of the device shown in 60 Fig. 3.

While the foregoing description has specifically set forth the invention, it is to be understood that numerous changes in the shape, size, and materials may be resorted to 65 without departing from the spirit and scope of the invention as claimed hereinafter.

Having thus described my invention, what I claim as new is:

A fastener of the character described comprising a jacket, a bail at one end of the jacket, a U-shaped member arranged within the said jacket, a compressible spring arranged on the said U-shaped member and being adapted to impinge against the inner 70 side of the jacket to maintain the U-shaped member retracted, said jacket being provided with openings to permit the leg portions of the said U-shaped member to protrude exteriorly thereof, and a button engager secured to the free ends of the said U-shaped member. 75

In testimony whereof I affix my signature.

SHERMAN BELVEAL.
